MAIL CHUTE

Martin Katz, New York, N. Y.

Application June 7, 1948; Serial No. 31,564

3 Claims. (Cl. 193--8)

1 This invention relates to mail chutes and especially to those mail chutes which are installed in tall buildings.

One of the principal disadvantages inherent in virtually every installation currently in use is the fact that very frequently the letters jam in the chute and thereby block its further use. When the jamming takes place in an accessible part of the mail chute, it is a simple matter to remove the glass frame thereof and to break the jam.

At times, however, the jam occurs in an inaccessible part of the mail chute, to wit, between the ceiling and the floor which lies immediately above it. When jamming occurs at this point, removal of the glass frame of the chute must be followed by the insertion of a long pole into the chute to force the jammed letters through. This is both a difficult and a delicate operation, since damage to the mail invariably occurs when the jam is tight.

The principal object of the present invention is the provision of a slidable mail chute section which is normally positioned between a floor and the ceiling below it and which is movable to a more accessible point in the mail chute system when a blockade of mail takes place therein. This slidable chute section is permanently installed in the mail chute system and it normally occupies the space between adjoining floors. It is only when the mail jam occurs between a floor and its adjacent ceiling, that is, in said slidable section, that it is pulled downwardly to an accessible place and there opened to unlock the jam. This device eliminates the need and use of a long pole to break through the jam. The advantages are manifold.

Another object of this invention is the provision of a housing for said slidable member which is permanently affixed to the floor structure and which is adapted to prevent a leakage of water or the entry of other foreign matter into the chute system.

A further object of this invention is the provision of a mail chute of the character described, in which the sections from one floor to the next are gently tapered in one continuous taper that extends the full distance between adjoining floors to facilitate the passage of mail therethrough.

A preferred form of this invention is shown in the accompanying drawings, in which:

Fig. 1 is a fragmentary face view of a mail chute in which the device herein claimed is incorporated, the floors through which said mail chute extends being shown in section.

2 Fig. 2 is a longitudinal section through the mail chute shown in Fig. 1.

Fig. 3 is a fragmentary vertical section through the upper section of the mail chute shown in Fig. 2 taken on a plane which is normal to the plane of the section of Fig. 2.

Fig. 4 is a fragmentary detailed view in section of the side walls of that part of the mail chute which lies between floors, and drawn to an enlarged scale.

Fig. 5 is a fragmentary horizontal section therethrough on the line 5--5 of Fig. 1.

Fig. 6 is a similar section taken on the line 6--6 of Fig. 1.

Fig. 7 is a view similar to that of Fig. 6, showing the entire chute and not merely one side thereof as does Fig. 6.

Fig. 8 is a front view of the slidable mail chute section herein claimed.

Fig. 9 is a top view thereof.

Fig. 10 is a front view similar to that of Fig. 8, showing the door on said mail chute section in partly open position.

Referring now to the first two figures of the drawing, it will be seen that the mail chute under consideration includes an outer casing or facia 10 on which is mounted a letter drop 11, glass panels 12, and a pair of frames 13 supporting the glass panels on said casing. The casing 10 extends from a little above the ceiling line 21 on one story to a little below the floor line 20 on the story below. Between each story, i. e., between the ceiling of one story and the immediately adjacent floor above it and confined within the casing 10 is a thimble or flashing 22 which is flared outwardly at the bottom adjacent the ceiling of the lower story to accommodate and embrace the top end of the casing or facia below it. The top of the thimble extends into the bottom end of the casing above it. It is therefore apparent that any flow or leakage of water would necessarily be prevented from entering the casing.

It will be apparent from examination of Figs. 5, 6, and 7 that casing 10 comprises a pair of side members to which the face plate, glass panels, and panel frames may be attached. Casing 10 also serves as a track and more particularly a pair of tracks, one on each of its two side members, to position the chute therein. It will be noted that formed on the inside of these two side members that comprise the casing is a pair of L-shaped flanges 25. Slidably mounted between each pair of flanges, and between said flanges and the side plate to which they are connected, is a plate 30 which supports the chute 31 by means

of brackets 32 which are disposed between and are connected to said slidably mounted plate and said chute. These slidable plates are movable longitudinally of the casing, and it is by this means that each chute section may be properly installed in its respective casing. Once the installation is complete, there is no need for any sliding or other relative movement between the slidably mounted plates and the chutes supported thereby on the one hand and the casing on the other.

The chute 31 is of conventional cross-sectional shape, that is, it comprises a U-shaped channel member having inwardly turned ends 35. A face plate 36 is affixed to the front of said channel-shaped chute, and more particularly to its inwardly turned end portions, thereby closing the channel and providing a substantially rectangular closed chute. It will be understood, however, that this front plate 36 is mounted on the chute only between a floor and its adjacent ceiling, and hence its length corresponds to the parts not covered by glass panels.

It has been stated that each chute section 31 is conventional in cross-sectional shape. Its length, however, is not conventional since it extends the full distance from below the floor line of one story to above the floor line on the story above, and more particularly from the thimble on one floor to the thimble on the next floor. In conventional mail chutes a plurality of chute sections is provided between adjacent floors, and each section is tapered at its ends to cooperate with the succeeding section. In the present invention each long chute section is provided with a gentle taper that enables its lower end to enter the upper end of the section below it, and enables its upper end to receive the lower end of the section above it. It is this unbroken taper extending the full distance from one floor to the next floor that aids to prevent jamming of the mail.

The between-floors attachment which constitutes the most important feature of the present invention is best shown in Figures 8, 9 and 10 of the drawing. It will there be seen that this member comprises a channel-shaped casing 40 having a door 41 slidably connected thereto. The casing has inwardly-turned flanges 42 which engage U-shaped flanges 43 on the door 41, and it is the inter-engagement of said flanges 42 with the U-shaped flanges 43 that provides the means by which the door is slidably mounted on the casing.

Locking means is provided to prevent relative movement between the casing and its door, and one form of said locking means is shown in the drawing to comprise a sliding bolt 45 mounted on the door which is adapted to enter into engagement with a bolt-receiving member 46 mounted on the casing. A second sliding bolt 47 is provided to engage a bracket or catch 48 which is connected to one of the slidably mounted plates of the chute construction to prevent relative movement between the between-floors attachment, which is shown in the last three figures of the drawing, and the chute construction.

It will be seen in Fig. 2 that casing 40, together with its door 41 and its two bolts 45 and 47, is slidably mounted within chute 31. The normal position of this slidable member is shown at the upper end of the chute construction shown in Fig. 2. This normal position is what may be termed a between-floors position and it is at this point that mail-jamming proves the most trouble-

some. It will be seen that engagement of bolt 47 with bracket 48 supports the sliding member in the chute in said position. At the lower end of the chute construction shown in Fig. 2, another sliding member is shown in a more accessible position, that is, between the ceiling and the floor below it. In order to bring the sliding member into this position, bolt 47 must be caused to disengage catch 48 and the sliding member may then be brought downwardly either by gravity or by a simple pulling or pushing force applied to it. When it reaches the more accessible position, the second bolt 45 may be drawn and the sliding door 41 may then be moved into open position, thereby exposing the inside of casing 40.

To insure proper between-floors positioning of the slidable member, each chute section 31 is provided at its upper end with a flange or bead 50. When it is desired to return the slidable member to its normal position shown at the top of Fig. 2, it is moved upwardly until contact is made with bead 50 on the chute section 31 in which the slidable member is mounted. Bolt 47 has ridden along the cam face of keeper member 48 and has snapped into place under the urgency of the spring and the device thereby assumes a fixed operative position.

The position which the sliding between-floors member occupies relative to the chute sections proper is best seen in Fig. 2. It will be noted at the top of said figure that when this sliding member occupies its between-floors position, which is its normal position, the lower end of the upper chute section extends part way into it and the said sliding member extends wholly within the upper end of the lower chute section. Hence it may be said that the sliding member extends between the two telescoping chute sections, the lower end of the upper chute constituting the inner member, the sliding member constituting the intermediate member, and the upper end of the lower chute constituting the outer member. (See Fig. 3.)

It will be understood that the foregoing is a description of a preferred form of this invention and that this form is susceptible of many modifications within the broad scope of the invention. For example, the locking mechanism by which the sliding door is locked in closed position on the slidable between-floors member may assume other forms than that shown in the drawing. A sliding bolt is obviously but one type of locking mechanism and many other types will be found equally suitable. The same is true of the locking mechanism by which the slidable member is held in between-floors position. Here too a sliding bolt is shown but it will be understood that other types of locking mechanism may also be used. As another illustration, the shape of the thimble as shown in the drawing is not critical except to the extent that its upper end must necessarily be of a size which enables it to fit into the chute casing which extends above it, and its lower end is of a size which enables it to receive and embrace the upper end of the chute casing which lies below it. The thimble shown in the drawing is provided with a flared skirt at its lower end to accommodate the upper end of the chute casing which lies below it. It will be apparent that an enlarged lower end may be provided in the thimble by means other than flared skirt means. It will also be apparent that it is immaterial whether the flare is provided at the lower end of the thimble or at the lower end of the chute casing. In either case, the upper end of the thimble

would extend into the lower end of the chute casing which is disposed above it, and the lower end of the thimble would extend around the upper end of the chute casing which is disposed below it.

The term between-floors as used herein is intended to designate the space or area which lies between each floor surface and the ceiling surface which lies immediately below it.

Having thus described my invention, what I claim as new and desire to secure by Letters Patent, is:

1. A mail chute for a multi-storied building structure having floors and ceilings, comprising a plurality of stationary tapered chute sections each of which extends the full distance from one floor to the next floor, the lower end of each stationary chute section extending into the upper end of the stationary chute section below it and an auxiliary movable chute section which is normally disposed between the telescopic walls of the lower end of each chute section and the upper end of the chute section below it, said movable chute section being slidably and removably mounted in the upper end of a chute section between a floor and an adjacent ceiling whereby said movable chute section may be lowered to a more accessible place in the stationary chute section when a letter-jam occurs in said movable chute section, a door being provided in the movable chute section to render any letters damaged therein more accessible from the outside, said movable chute section being also pro-

vided with locking means for holding said door in normal, closed position relative thereto.

2. A mail chute in accordance with claim 1, in which the movable chute section is provided with locking means for holding said movable chute section in its normal position between a floor and its adjacent ceiling.

3. In a mail chute of the type having a plurality of stationary chute sections one above the other, with the bottom of each chute section except the lowermost extending into the top of the next lower chute section, with the walls of their adjacent ends laterally spaced apart; a movable auxiliary chute member which is slidably mounted in the upper end of each stationary chute section, the upper end of the movable chute member receiving the lower end of the stationary chute section lying above it, said movable chute member being movable to selected size in the last-mentioned stationary chute section.
